UNITED STATES PATENT OFFICE

LÜDER SCHRIEVER, OF DANZIG-LANGFUHR, DANZIG, AND ALFRED MICHAEL, OF BREMEN, GERMANY

PORTHOLE FOR SHIPS

Original application filed January 27, 1927, Serial No. 164,064, and in Germany June 23, 1926. Divided and this application filed February 29, 1928. Serial No. 258,053.

The invention relates to a special modification or constructional form of the ship's porthole according to my copending application filed January 27, 1927, Serial No. 164,064, of which this application is a divisional.

According to the known construction, each individual ship's porthole has its own suction device, which is in direct communication with the air passage of the portlight, whereas according to the invention, the air passage of the portlight communicates with a pipe from which a ventilator or fan sucks. As compared with what is known, this arrangement has the advantage that the shutter of the portlight can be closed and opened without the suction device being removed. Several portholes may also be connected to this suction device.

The invention is shown in the accompanying drawing by way of example, in which:

Fig. 1 is a vertical cross section through a ship's porthole according to the invention.

Fig. 2 is an elevation of the ship's porthole (viewed from within).

Similar characters of reference are employed throughout the several views to indicate corresponding parts.

A ship's porthole with a ventilating arrangement according to the invention consists essentially of a frame 1, which contains the glass disc or pane 2 of the ship's porthole and which is pressed in any suitable manner against a frame 3 connected to the wall of the ship with interposed packing means. In this frame, passages 4 are provided, which communicate through openings 5, 6 with the outer air, closing members for instance, balls 7, preventing the penetration of water when it rises to the level of the porthole. The path of the air current from the outside is indicated by the arrow A. It has already been proposed to provide on the inside of such a frame a strong shutter 8, by which the porthole can be completely closed. This shutter is adapted to swing about a bolt 9 and is tightened by a screw bolt 10 by means of a fly nut 11. The screw bolt 10 is adapted to swing about a bolt 12.

There is provided on the periphery of the

frame 1 a slot 13, which is connected to a ventilating device 15 by a tube 14.

This arrangement enables the shutter 8 to be moved without the suction device being removed. It is also possible to connect several ship's portholes to a single suction device.

Having now fully described the invention what is claimed as new and desired to be secured by Letters Patent is:

1. A ship's porthole, comprising in combination an outer frame fixed to the wall of the ship, a glass pane, a second frame surrounding the glass pane between the glass pane and the outer frame on the ship's wall, air passages in the second frame, a suction opening in the said second frame on the peripheral surface of the porthole and in the upper part of the said frame, openings in the second frame on the outer side thereof, connected by the said air passages to the suction opening, closing members in the second frame for closing the openings on the outer side under the action of the water on the outside of the porthole, a shutter pivotally mounted on the wall of the ship for closing the porthole from the inside thereof, a casing, a fan in the casing, a pipe connection between the suction opening and the casing containing the fan, so that the shutter may be closed without removing the casing.

2. A ship's porthole comprising in combination an outer frame fixed to the wall of the ship, a second inner hollow frame detachably connected with the first frame, a glass pane surrounded by the second frame, the hollow frame having inner and outer annular ventilating channels, a partition separating the inner and outer channels from each other and having holes establishing communication between the inner and outer annular channels in the lower part of the second frame, means for closing the holes in the partition when acted upon by water pressure from the outside of the porthole, a suction device situated a considerable distance from the porthole, and a pipe establishing communication between the suction device and the inner channel.

3. A ship's porthole comprising in combi-

nation an outer frame fixed to the wall of the ship, a second inner hollow frame detachably connected to the first frame, a glass pane surrounded by the second frame, a partition in the hollow part of the second frame to form inner and outer ventilating annular channels and having holes establishing communication between the channels in the lower part of the second frame, means for closing the holes in the partition, the closing means comprising metal balls, a suction device situated a considerable distance from the port-hole and a pipe having one end in communication with the suction device and the other end enlarged and communicating with the inner annular channel.

In testimony whereof we have signed our names to this specification.

LÜDER SCHRIEVER.
ALFRED MICHAEL.
